DESIGN FOR A PHONOGRAPH CABINET OR SIMILAR ARTICLE

Joseph M. Lucarelle and Charles Ecklund,
Bridgeport, Conn., assignors to Dictaphone Corporation, New York, N. Y., a corporation of
New York

Application February 10, 1933. Serial No. 47,178

Term of patent 14 years

To all whom it may concern:

Be it known that we, JOSEPH M. LUCARELLE, and CHARLES ECKLUND, both citizens of the United States; both resident at Bridgeport, in the county of Fairfield and State of Connecticut, have invented a new, original, and ornamental Design for a Phonograph Cabinet or Similar Article, of which the following is a specification, reference being had to the accompanying drawing, forming part thereof.

The figure is a perspective view of a phonograph cabinet, showing our new design.

We claim:

The ornamental design for a phonograph cabinet or similar article, as shown.

In testimony whereof, we have signed our names to this specification this 7th day of February, 1933.

JOSEPH M. LUCARELLE.
CHARLES ECKLUND.
